UNITED STATES PATENT OFFICE.

DAVID D. GORDON, OF CHICAGO, ILLINOIS, ASSIGNOR TO YOST ELECTRIC MANUFACTURING COMPANY, OF TOLEDO, OHIO.

WALL-SWITCH.

1,149,362.

Specification of Letters Patent. Patented Aug. 10, 1915.

Application filed February 12, 1914. Serial No. 818,236.

To all whom it may concern:

Be it known that I, DAVID D. GORDON, a citizen of the United States, residing at Chicago, in the county of Cook and State of Illinois, have invented a certain new and useful Improvement in Wall-Switches, of which the following is a full, clear, concise, and exact description, reference being had to the accompanying drawings, forming a part 10 of this specification.

My invention relates to switching devices and has for its object the provision of a new and improved mechanical movement applicable to switches or other devices, but herein 15 more particularly described in connection with a switch as it is readily illustrated in this connection.

I have decided to more specifically illustrate my invention herein in connection with 20 a push button wall switch and when so applied it needs but one push button, which furnishes a novel feature.

Various applications of the invention will be readily apparent, for instance, its use in 25 connection with a pull socket or pendant switch, or devices other than electrical in their nature.

I will describe a form which my invention may take more particularly by referring to 30 the accompanying drawing illustrating such a form in which—

Figure 1 is a longitudinal sectional view of a switch constructed in accordance with my invention; Fig. 2 is a view similar to 35 Fig. 1, but showing the switch in a partially actuated condition; Fig. 3 is a sectional view on line a—a of Fig. 1, and Fig. 4 shows the movable switch element in its alternative position.

Referring more particularly to Fig. 1, I 40 show a switching device having a casing 1 and a front plate 2 adapted to be fastened to the wall, and having a protruding push button 3 serving both for make and break purposes. 45 Whenever the push button 3 is pushed inwardly it may, for instance, close the circuit. The button is automatically retracted. Then if the button 3 is again actuated it will open the circuit so that one push button suffices. 50 A spring 4 normally withdraws the push button to the position of Fig. 1. This push button has a longitudinal outwardly projecting pin 5. When the push button is moved toward the left the pin 5 rides on top of the trigger 6 until it reaches approximately 55

the position of Fig. 2, at which time the spring by pulling the push button downwardly causes the trigger 6 to revolve counterclockwise and permit the pin 5 to fall down to the bottom wall of the box 7, after which 60 time the spring continues to move the push button 3 to the right, the pin 5 continuing in its movement toward the right until it has passed away from the cam to the position it occupies in Fig. 1, at which time it is 65 again ready to slide over the cam, when the push button is next actuated. The push button 3 also carries a finger 8 and each actuation of the push button 3 will cause this finger 8 to move toward the left and up- 70 wardly until the trigger snaps, at which time there is a downward movement of the finger which later on continues toward the right back to the position illustrated in Fig. 1. This movement of the finger serves to 75 move a switch element 9 through an angle of ninety degrees for each actuation of the push button 3. This switch element is adapted in the position shown in Fig. 1 to close circuit through stationary contacts 10 80 and 11. If the switch element 9 is moved through an angle of ninety degrees, (this element always moving in a clockwise direction) the circuit through the contacts 10 and 11 will be opened. A further movement of 85 ninety degrees will again close the circuit and so on. Each actuation of the switch element 9 is of course by snap action, as it takes place at that particular time when the pin 5 trips the trigger 6. This actuation of 90 the switch element 9 is caused by means of a plurality of horizontally extending fingers 12 which are secured to the switch element. Just before the trigger is snapped the ele- 95 ment 8 rides on top of one of the fingers 12 and its downward movement causes the ninety degree rotation, which at the same time releases the element 8 from the finger 12 with which it has had engagement. Of course, some means should be provided to 100 prevent the element 9 from spinning and suitable frictional means such as a screw 13 may be employed or any other suitable device to retain the element in its various pre- 105 determined positions. A stop 14 is provided to prevent complete rotation of the element 6.

From what has been described it is thought the invention will be clear, and also that it is capable of a great variety of uses and a great diversity of applications.

Having however thus described one form which my invention may take, what I claim as new and desire to secure by Letters Patent is:

5. 1. In combination with a rotatable movable switch element adapted to occupy two normal resting positions, a reciprocating element having means to periodically engage and move said switch element by snap action, and trigger mechanism to effect snap action movement of said reciprocating element, said trigger mechanism including an abutment on said reciprocating element and a tiltable cam.
10. 2. An electric switch having a switch element adapted to occupy two normal resting positions, and means including tripping mechanism therefor to move said switch element by snap action from either alternative position to the other, and engaging said switch element only during the snap action portion of its movement.
15. 3. An electric switch having a switch element adapted to occupy two normal resting positions, and reciprocating means including tripping mechanism therefor to move said switch element by snap action from either alternative position to the other and engaging said switch element only during the snap action portion of its movement.
20. 4. An electric switch having a switch element adapted to occupy two alternative resting positions, manually operable means to move said switch element by snap action from either alternative position to the other and engaging said switch element only during the snap action portion of its movement,
25. and tripping mechanism to impart a snap action movement to said means throughout a portion of its stroke.
5. An electric switch having a switch element adapted to occupy two alternative resting positions, manually operable means to move said switch element by snap action from either alternative position to the other and engaging said switch element only during the snap action portion of its movement, tripping mechanism to impart a snap action movement to said means throughout a portion of its stroke, and means for retaining said switch element in either of its alternative positions.
10. 6. An electric switch having a rotatably mounted switch element adapted to occupy a plurality of normal resting positions, and means including tripping mechanism for moving said switch element by snap action from one resting position to the other, said means being disengaged from said switch element during the recoil movement thereof.
15. 7. An electric switch having a rotatable switch element, a manually operable reciprocating element to control said switch element, a tripping mechanism to effect a snap action movement of said reciprocating element.

In witness whereof, I hereunto subscribe my name this 14th day of January, A. D., 1914.

DAVID D. GORDON.
